PIVOTAL SLIDABLE WINDOW

John Gurniak, Elkins Park, Pa., assignor to Michael Flynn Manufacturing Company (also known as Michael Flynn Manufacturing Co.), Philadelphia, Pa., a corporation of Pennsylvania

Filed Apr. 5, 1960. Ser. No. 20,126

7 Claims. (Cl. 20—42)

This invention relates to a horizontally slidable window assembly, and it more particularly relates to an assembly wherein the window is also adapted to be pivoted.

Horizontally slidable windows have gained increasingly wide acceptance and many new homes are provided therewith. This is due to many factors among which are their relative ease of manufacture, their moderate cost and their ease of installation. However, in use, it has been found that it is most difficult to wash such windows because of the difficulty in reaching all areas of the outer surface. To adequately wash such windows, it is usually necessary to either remove the window panels from the window frames or to wash the windows from the outside. Removing and replacing the window panels is an irksome and tedious job especially for a housewife, while washing the windows from the outside is a hazardous and awkward procedure which most people would prefer to avoid.

It is one object of the present invention to overcome the aforesaid difficulties by providing a horizontally slidable window assembly wherein the slidable window may also be pivoted to extend into the room and thereby be easily accessible on both sides.

Another object of the present invention is to provide a window assembly of the aforesaid type which is relatively simple in structure, easy and economical to manufacture, easy to install and easy to use.

Other objects and many of the attendant advantages of this invention will be readily appreciated as the same becomes better understood by reference to the following detailed description when considered in connection with the accompanying drawings wherein:

FIG. 1 is a front elevational view of a window assembly embodying the present invention;

FIG. 2 is a sectional view taken on line 2—2 of FIG. 1;

FIG. 3 is a sectional view taken on line 3—3 of FIG. 1;

FIG. 4 is an enlarged, front elevational view, similar to FIG. 1, but with parts broken away to show various details;

FIG. 5 is a fragmentary sectional view taken on line 5—5 of FIG. 4;

FIG. 6 is a fragmentary view taken on line 6—6 of FIG. 5;

FIG. 7 is a fragmentary sectional view taken on line 7—7 of FIG. 4;

FIG. 8 is a fragmentary sectional view taken on line 8—8 of FIG. 4;

FIG. 9 is a fragmentary view taken on line 9—9 of FIG. 8;

FIG. 10 is a fragmentary sectional view taken on line 10—10 of FIG. 4;

FIG. 11 is a fragmentary sectional view taken on line 11—11 of FIG. 4;

FIG. 12 is a front elevational view similar to FIG. 1, but showing the window in open position and with parts broken away to show various details;

FIG. 13 is a fragmentary sectional view taken on line 13—13 of FIG. 12;

FIG. 14 is a view similar to FIG. 13, but showing the window pivoted into perpendicular position;

FIG. 15 is an enlarged, fragmentary view of the cam element of FIG. 14;

2

FIG. 16 is a fragmentary sectional view taken on line 16—16 of FIG. 12;

FIG. 17 is a view similar to FIG. 16 but showing the window in pivoted position;

FIG. 18 is an enlarged view of the cam shown in FIG. 17;

FIG. 19 is a fragmentary sectional view taken on line 19—19 of FIG. 12;

FIG. 20 is a fragmentary sectional view taken on line 20—20 of FIG. 12;

FIG. 21 is a fragmentary perspective view of a portion of the assembly;

FIG. 22 is a fragmentary sectional view taken on line 22—22 of FIG. 4;

FIG. 23 is a fragmentary sectional view taken on line 23—23 of FIG. 1; and

FIG. 24 is a sectional view taken on line 24—24 of FIG. 23.

Referring in greater detail to the various figures of the drawings wherein similar reference characters refer to similar parts, there is shown a window assembly, generally designated 10, comprising a rectangular frame 12 in which is positioned one stationary window panel 14 and one slidable window panel 16, each of these panels comprising a rectangular frame with a glass pane therein in the standard manner.

The frame 12 includes an elongated channel 18 which acts as a guide for the sliding movement of panel 16 into and out of closed position. This guiding action is provided in conjunction with cylindrical guide feet (more fully described hereafter) mounted on a flange 22 extending laterally from an upward extension 24 of the frame of the panel 16. An upright flange 26 also extends upwardly from the panel frame but in spaced relation to extension 24. The flange 26 is higher than extension 24 and acts as a cover for the upper edge of the slidable panel.

The extension 24 is also provided with a longitudinal channel 28 in which is positioned a weatherstrip 30. This weatherstrip 30 is preferably made of wool fibers although any other material such as metal, vinyl, polyethylene or the like may also be used. The channel 28 is open on its inner side and the weatherstrip 30 projects through this opening into a position where it slidably abuts against the adjacent side wall defining channel 18.

The aforesaid cylindrical guide feet supported by the flange 22 are indicated at 32, each of these guide feet 32 being secured to the flange 22 by means of rivets 34 or the like. The feet 32 slidably engage the inner surfaces of the two opposite side walls defining channel 18.

At the rearward edge of flange 22 is secured a pivot member 36, this member 36 being connected to the flange 22 by a rivet 38 or the like. The member 36 is provided with a pivot finger 40.

At the lower edge of panel 16 are provided a pair of cylindrical guide feet 42 similar to feet 32 except that they are provided with undercut V-shaped notches 44. These notches are provided to engage an upstanding guide rail 45 extending up from the bottom portion of the window frame 12.

At the rear end of the lower edge of the panel 16 is provided a plate 46 retained in position by a screw 48 or the like. The plate 46 is provided with a depending pivot finger 50. The plate 46 is also provided with an undercut recess 52 to permit the plate 46 to be raised out of engagement with the guide rail 45.

Positioned on the bottom portion of the window frame, to the right of but adjacent the left hand end of the panel 16 when in closed position, is a cam block 54. This block 54 includes an inclined edge 56 and a straight top edge 58. An auxiliary cam portion 59 fits on the top edge of rail 45. The block itself is linearly adjustable

by means of a lateral flange 60 having an elongated slot 62 through which extends a set screw 64. The screw 64, when loosened, acts as a guide to permit linear adjustment of the block 54 in either direction for the length of the slot 62. Then when the block has been adjusted to the desired position, the screw 64 is tightened to hold the block securely in place.

The bottom portion of window pane 16 is also provided with a longitudinal channel 66 having a side opening from which projects a weatherstrip 68 seated in the channel. The strip 68 is similar to the strip 30 and is adapted to sealingly abut an upstanding flange 70 on the lower portion of the window frame.

Whereas the panel 16 is movable relative to the window frame 12, the panel 14 is fixed in the window frame and is positioned behind the panel 16 to permit overlapping thereof. Adjacent the left end of the panel 14 (as viewed in FIGS. 1, 4 and 12), there is positioned in the channel 18 a cam track 72. This cam track 72 is provided with a longitudinal slot having a relatively wide major portion 72 and a relatively narrow minor portion 76. At the end of portion 76 is provided an enlarged circular opening 78. The cam track is stepped at the junction of the slot portions 74 and 76, as indicated at 80. This step 80 is necessary because when the relatively wide member 36 rides in wide slot portion 74 the parts are in a different section of the mathematical curve of rise than when the relatively narrow finger 40 rides in the narrow slot portion 76. The step 80 takes care of the differential and thereby keeps the curve of rise smooth and continuous. An upstanding stop flange 82 is provided at the end of the cam track.

On the inner lower edge of window frame 12, in vertical alignment with cam track 72, is a similar cam track 84. This cam track 84 is also provided with an elongated slot but only a minor portion thereof is relatively wide, as at 86, while the major portion is relatively narrow, as at 88. At the end of slot portion 88 is provided a circular opening 90, similar to opening 78. The cam track 84, is furthermore, not stepped but extends in a straight inclined direction up to a straight plateau portion, the opening 90 being positioned in this plateau portion.

At the right hand edge of panel 16 (as viewed in FIG. 1) there is provided a latch means 92. This latch means comprises a generally U-shaped handle 94 having one arm 96 adapted to engage a lateral flange 98 on the corresponding vertical edge of the panel 16, and having its other arm 100 provided with two extensions 102 and 104 (see FIG. 23). The extension 102 is provided at its end with an enlarged, cylindrical portion 106 engageable within a groove 108 in the panel 16 whereby there is formed a hinged joint between the latch means and the panel. The other extension 104 is provided with a hooked end 110 releasably engageable with a flange 112 on the corresponding vertical edge of the window frame 12. A spring 114 is connected to arm 100 and bears against the edge of flange 98. This spring, thereby biases the latch into locking position against flange 112 (as indicated in full line in FIG. 23).

The left hand vertical edge of panel 16 (as viewed in FIG. 1) is provided with a channel 116 in which is provided a weatherstrip 118 similar to that shown at 68. The opposite vertical edge of panel 16 is also provided with a channel 120 having a weatherstrip 122 of similar type. This channel 120 is provided in the rearward edge of the framework of the panel 16 (see FIG. 22) and the weatherstrip 122 is adapted to frictionally engage against a straight wall 124 defining one edge of the open inner side of a hollow, vertical post 126 in the window frame. This wall 124 is spaced inwardly from the plane of the inclined wall 128 defining the opposite edge of the open inner side of post 126.

The rearward edge of the framework of panel 16, in addition to channel 120 and weatherstrip 122, is provided with a flange 130 having an inclination comple-

mentary to that of wall 128 so that it is slidably engageable therewith to limit the forward movement of the panel 16 (as illustrated in FIG. 22).

In operation, when it is desired to merely open or close the window, this is done in the normal manner by easily sliding the panel 16 back and forth to the desired position. However, when it is desired to move the window into the pivotal position, this can be easily done by giving the panel 16 an extra shove. This provides the slight additional force required to raise the panel on its cam tracks whereby member 36 and the finger 40, which is of rectangular cross-sectional shape, are guided first by the wide slot portion 74 and then by the narrow slot portion 76. At the same time, the finger 50, which is also of rectangular cross-section, engages first in slot portion 86 and then in slot portion 88 as it moves up the inclined track 84. Simultaneously, the foot 42 at the forward end (or right hand end as viewed in FIG. 4) moves onto the cam block 54 while the notch 44 rides over auxiliary cam portion 59. The upward force exerted by the block 54, in conjunction with the force applied by cam track 76, acts to lift the entire panel 16 within the window frame.

The fingers 40 and 50 move along their respective slots until they reach their respective openings 78 and 90. Since the fingers 40 and 50 are rectangular in cross-section, they cannot be rotated within their respective slots until they reach their respective openings 78 and 90. Then, however, they can be rotated into the full line positions shown in FIGS. 15 and 18. In these positions, they are locked against movement out of the openings.

When the fingers 40 and 50 are within the openings 78 and 90, they are in pivotal position. Therefore, the panel 16 can be pivoted into a position transverse to the window frame (as indicated in FIGS. 14 and 17). In this pivotal position the fingers are in the locked position within their respective openings (as shown in FIGS. 15 and 18 and as described above). Therefore, the panel can be pivoted to any desired position without danger of falling out of the window frame. Thereafter, when it is desired to either remove the panel or to move it back to closed position, the panel is pivoted back to its normal position parallel with the window frame, at which time the fingers 40 and 50 are again in position to slide into the slots of their respective cam tracks.

Obviously many modifications and variations of the present invention are possible in the light of the above teachings. It is, therefore, to be understood that within the scope of the appended claims, the invention may be practiced otherwise than as specifically described.

What is claimed as the invention is:

1. A window structure comprising a rectangular frame having at least one rectangular window panel movable therein, said window frame including oppositely positioned channels, said window panel having oppositely positioned guide means slidable in corresponding channels, slidable pivot fingers on opposite edges of said panel, said fingers each being elongated in shape and slidable in said channels, a cam block in at least one of said channels in the path of movement of said guide means, the corresponding guide means being slidable over the cam block to move said panel transversely of said frame, an inclined cam track in each of said channels, said cam tracks being transversely aligned with each other at predetermined positions in said channels, said cam tracks each having a slot of a width slightly larger than the longitudinal width of the pivot finger movable in the corresponding channel and smaller than the length of said finger, said slot terminating in a circular aperture of a diameter slightly greater than the length of said finger.

2. A window structure comprising a horizontal rectangular window frame having at least one horizontally movable rectangular window panel therein, said window frame including an inner periphery defined by an upper horizontal channel and a lower guide rail, said movable

panel having upper and lower horizontal edges and forward and rearward vertical edges, guide means connected to the upper edge of said panel and movable in said upper horizontal channel, guide means connected to the lower edge of said panel and being in slidable engagement with said guide rail, upper and lower upwardly inclined cam tracks on said inner periphery of the window frame, each of said cam tracks being arranged in vertical alignment with each other, each of said cam tracks having a longitudinal slot therein terminating in a circular aperture, and a guide and pivot pin on each of the upper and lower edges of said panel, said pins being positioned adjacent the rearward edge of said panel and being rectangular in shape with a longitudinal width slightly smaller than the width of the slot in the corresponding cam track and a length larger than the width of the slot and slightly smaller than the diameter of said aperture, said pins being slidable in the slots and rotatable in the apertures of their corresponding cam tracks.

3. The window structure of claim 2 wherein a cam block is provided at a predetermined position on the lower portion of said inner periphery of the window frame, each guide block having an upwardly inclined cam surface corresponding to the cam surfaces of said cam tracks, and at least a portion of the guide means on the lower edge of said panel, adjacent the forward edge thereof, being arranged to engage said cam block simultaneously with the engagement of said guide and pivot pins with said cam tracks to raise the forward portion of said panel simultaneously with the raising of the rearward 30 portion thereof.

4. The window structure of claim 2 wherein said guide means connected to the upper edge of the panel comprises a plurality of cylindrical feet mounted on a lateral flange extending from the upper edge of said panel, and said 5 guide means connected to the lower edge of the panel comprises a plurality of feet each of which is provided with an undercut notch to slidably receive said guide rail.

5. The window structure of claim 2 wherein said window frame is provided with a central vertical post, said post having a stop means therein to engage a complementary stop means on said panel to limit forward slideable movement of said panel.

6. The window structure of claim 2 wherein said panel 15 is provided with a latch means for releasably locking said panel to said window frame in a predetermined closed position.

7. The window structure of claim 2 wherein there is a stationary window panel in said window frame, said 20 stationary panel being in an offset plane relative to said movable panel to permit said movable panel to slide into and out of overlapping position relative to said stationary panel.
